UNITED STATES PATENT OFFICE.

WILLIAM J. MCKENZIE, OF NEDERLAND, COLORADO.

RAIL-JOINT CHAIR.

1,107,540.

Specification of Letters Patent. Patented Aug. 18, 1914.

Application filed January 7, 1914. Serial No. 810,803.

To all whom it may concern:

Be it known that I, WILLIAM J. MCKENZIE, a citizen of the Dominion of Canada, residing at Nederland, in the county of 5 Boulder and State of Colorado, have invented certain new and useful Improvements in Rail-Joint Chairs, of which the following is a specification, reference being had to the accompanying drawings.

10 This invention comprehends certain new and useful improvements in rail joint chairs and has for its primary object to provide a rail joint chair which will be of extremely simple construction and operation and which 15 will include a wedge member which serves to draw together, the parts of the rail joint chair and cause the same to clamp the rail ends secured in said chair.

Another object is to provide a device of 20 this character which will be constructed in such manner that as the parts are forced together, the wedge member will draw downwardly upon the sections of the rail joint chair and at the same time, force the rail 25 ends upwardly, thereby securely clamping the rail ends in position and preventing movement of the same as the wheels of the rolling stock pass over the joint.

A further object is to generally improve 30 and simplify the construction and operation of devices of this character and increase the efficiency of the same, without increasing the cost of manufacture thereof.

With the above and other objects in view, 35 my invention consists in certain novel constructions, combinations, and arrangements of parts to be hereinafter more fully described, claimed, and illustrated in the accompanying drawings, in which,

40 Figure 1 is a transverse sectional view through my device in use; and Fig. 2 is a fragmentary side elevational view of one of the rail joint chair members, looking at the inner face thereof.

45 Referring more specifically to the drawings in which similar reference characters designate corresponding parts throughout the several views, 1 and 2 designate the rail joint chair members which include the 50 standing portions 3 for engagement against the web portions of the rail ends 4 and the lower portions 5 for engagement upon opposite sides of the base portions of said rail ends.

55 The base portion 6 of the rail joint chair member 1 is of such width as to extend be-

neath the entire base portions of the rail ends 4 and has its upper face inclined transversely, the purpose of which will presently appear. The rail joint chair member 1 also 60 has its under face cut away along its free or inner longitudinal edge to form a channel 7 to receive the narrow base portion 8 of the rail joint chair member 2.

It will be understood that the upstanding 65 or web engaging portions of the rail joint chair members 1 and 2 are provided with the usual bolt openings 9 to receive the bolts 10 for drawing together said rail joint chair members and causing the same to clamp and 70 hold together, the rail ends 4.

In order to draw the rail joint chair members 1 and 2 tightly against opposite sides of the web portion of the rail ends 4 as the nuts 11 are tightened upon the bolts 75 10, I have provided a wedge member 12 positioned beneath the base portions of the rail ends 4 and resting upon the inclined upper face of the base portion 6 of the rail joint chair member 1, which wedge member 12 80 will also serve to force the rail ends 4 upwardly as the wedge member 12 is forced to proper position by the drawing together of the rail joint chair members 1 and 2, said wedge member 12 riding upwardly upon the 85 inclined upper face of the base portion 6.

The rail joint chair members 1 and 2 have the outwardly directed perforated flanges 13 to receive the usual railway spikes 14. The rail joint chair members 1 and 2 are 90 also provided with the downwardly directed perforated flanges 15 between the outwardly directed perforated flanges 13 and adapted for engagement between the ties 16. The downwardly directed perforated flanges 15 95 are adapted to receive the bolts 17 extended transversely beneath the rail ends 4 and the rail joint chair members 1 and 2 and are adapted to draw toward one another the rail joint chair members 1 and 2 and retain the same in proper relation to one another and to the rail ends 4.

From the foregoing, it will be seen that I have provided a rail joint chair which will be of extremely simple construction 105 and operation and which will securely clamp the rail ends in position and prevent movement of the same by wheels of the rolling stock passing over the joint. Further, it will be clearly apparent that, owing to 110 the wedge member, and the construction of the rail joint chair members, they will not

be loosened and thereby allow play of the rail ends by the strain to which they are subjected by rolling stock passing over the joint, as is the case with the forms of rail joint chairs now in general use.

While I have shown the preferred embodiment of my invention, it will be understood that minor changes in the details of construction and arrangement of parts may 10 be made within the scope of the appended claims without departing from the spirit of my invention or sacrificing any of the advantages of the same.

What I claim is:—

15 1. A device of the class described comprising a rail joint chair member having an upstanding portion and a base portion provided with an inclined upper face, a wedge member positioned upon said inclined upper face, a second rail joint chair member having an upstanding portion and a base portion, the upstanding portions of the rail joint chair members being adapted for engagement with the opposite faces of 20 the web portions of meeting rail ends, the upstanding portion of the second member being also adapted to bear against one edge of said wedge member, and means for se- 25

curing the upstanding portions of said members against the meeting rail ends.

2. A device of the class described comprising a rail joint chair member having an upstanding portion and a base portion provided with an inclined upper face, said base portion being provided with a channel 30 along its inner lower longitudinal edge, a second rail joint chair member having an upstanding portion and a base portion, said base portion being adapted for engagement in said channel in the base portion of the 35 first member, the upstanding portions of the rail joint chair members being adapted for engagement with opposite faces of the web portions of meeting rail ends, a wedge member positioned upon the inclined upper 40 face of the base portion of the first member, and means for securing the upstanding portions of the rail joint chair members against the meeting rail ends.

In testimony whereof I hereunto affix my signature in the presence of two witnesses.

WILLIAM J. MCKENZIE.
